UNITED STATES PATENT OFFICE.

GEORGE C. PRINGLE, OF BILOXI, MISSISSIPPI.

TOOL FOR INSTALLING TURPENTINE-CUPS.

1,073,517.

Specification of Letters Patent. Patented Sept. 16, 1913.

Application filed May 17, 1911. Serial No. 627,651.

To all whom it may concern:

Be it known that I, GEORGE C. PRINGLE, a citizen of the United States, residing at Biloxi, in the county of Harrison and State 5 of Mississippi, have invented a new and useful Tool for Installing Turpentine-Cups, of which the following is a specification.

This invention relates generally to tur- 10 pentine tools, and particularly to a tool adapted for installing turpentine cups.

Heretofore, in order successfully to prepare the tree faces for the reception of a cup, it has generally been necessary to em- 15 ploy two ax-men for the purpose, one right- and the other left-handed, and using axes particularly adapted for their respective wielders. This is due to the fact that ambidextrous ax-men are scarce, and that 20 the average ax-man has trained himself to work from one side only. As is well known, right-handed ax-men predominate in numbers, and so it frequently happens that an operator or contractor cannot supply him- 25 self with a left-handed one, the result being that he is hampered in his work and loses much valuable time for which he has to pay for the services of unskilled and thus unsatisfactory labor.

30 It is the object of the present invention, in a novel and practical manner, to obviate the above objections by providing a tool that shall be adapted to be used by either a right or a left-handed ax-man, the construction of which will materially facilitate the operation and lessen the labor of forming the tree faces, and which shall reduce to the minimum the danger of cutting too deep and thus injuring the trees.

40 With the above and other objects in view, as will appear as the nature of the invention is better understood, the same consists in the novel construction and combination of parts of a turpentine tool, as will be 45 hereinafter fully described and claimed.

In the accompanying drawing forming a part of this specification, and in which like characters of reference indicate corresponding parts, Figure 1 is a view in perspective 50 of a tool constructed in accordance with the present invention. Fig. 2 is a longitudinal sectional view. Fig. 3 is a transverse sectional view on the line 3—3 of Fig. 2. Fig. 4 is a rear elevation of the tool.

55 The tool comprises a cutting head design-

nated generally 1, a shank 2, and a neck 3 connecting the head and the shank. As shown in Fig. 3, the cutter head comprises a straight front cutting edge 4 and a pair of curved lateral cutting edges 5, that merge 60 into the neck 3, the latter constituting a continuation of the shank 2, which is disposed in approximate parallelism with the front edge 4. The cutter head is a hollow structure of an approximately irregular 65 elliptical form, providing thereby ample space for the escape of chips in the use of the tool, whereby any loss of time which would result from clogging is prevented.

One of the essential features of the in- 70 vention is the manner of disposing the side cutting edges 5 relative to the front cutting edge, the former edges, as shown in Fig. 2, being disposed approximately at an angle of 45 degrees to the front cutting 75 edge 6, so that a clean initial cut, known as the "first streak" may be formed, which will accurately define the limit of the lateral cut, in one direction of the face.

The cutting edges 5, as shown in Fig. 4, 80 terminate some distance short of the neck, thus further to permit the escape of chips.

The cutter head as a whole is combined with a handle 7 having adjacent one end an all-through slot 8 in which the neck fits, the 85 shank being disposed within a longitudinal channel 9 arranged in the handle on the side opposite that through which the neck is inserted, the inner wall 10 of the channel being shaped in such manner as to conform to 90 the adjacent portion of the shank. By this arrangement it will be seen that the force of the impact resulting from the use of the tool will have a tendency always to seat the shank in the channel, so that accidental dis- 95 connection of the parts in use will positively be precluded.

As will be obvious, in order to secure the above results, the cutter head as a whole should be comparatively thin, and to impart 100 the desired weight to the tool to enable it to deliver effective blows, the handle has combined with it at the end opposite that carrying the head, a spherical weight 11, which will in effect secure the same function as if 105 the head were made of thick metal.

In the use of the tool, the ax-man cuts his first streak, say on the left hand side of the center line of the two faces, this cut resem- 110 bling a half-auger hole, and the straight cut-

ting edge of the tool is then brought into play and will remove the bark up to the point which will be considered the median line of the two faces, and the operation is then repeated on the right hand side, and when the two faces are cleared of bark, the two incisions to receive the turpentine gutter are made with the straight edge of the cutter head in the same manner as that accomplished with the use of an ordinary broad ax, after which the gutter is placed in position within the incisions. This gutter may be of any preferred construction, such as that shown in the United States patent granted to me on July 5, 1910, No. 963,066.

From the foregoing description it will be seen that by the use of the tool of this invention, that any ax-man may use it with equal facility, in preparing either right or left hand faces, so that the necessity for the ax-man being ambidextrous is wholly eliminated.

Owing to the shape of the tool, it will be adapted to be used as a scraper, thus materially broadening the scope of its utility.

It will be noted that the side portions of the head converge backwardly toward the shank and they thus constitute means for abutting against one side of the handle while the shank is engaging the opposed side thereof. Thus the head of the tool is prevented from sliding toward or away from the handle. Furthermore, as the inclined lower edges of the head converge upwardly toward the shank, it will be seen that they permit the head to be tilted downwardly toward

the handle, thus to permit withdrawal of the shank from the handle.

I claim:

The combination with a handle, of a cutting element comprising, in a one piece structure, a shank, a cutting head thereon having a straight front face and side portions converging from the front face to the shank, said straight front face having a straight cutting edge and the side portions being formed with inclined cutting edges converging toward the shank and disposed in a plane that approximates an angle of 45 degrees to the straight front face of the cutting head, the cutting head and shank being connected by a straight neck disposed at right angles to the shank and adapted to be removably seated in the handle, said shank constituting means for engaging one side of the handle and said diverging side portions constituting abutments for the other side of the handle, to hold the head against sliding movement toward or away from the handle, the inclined lower edges of the head constituting means for permitting downward tilting of the head relative to the handle and the withdrawal of the shank from the handle.

In testimony that I claim the foregoing as my own, I have hereto affixed my signature in the presence of two witnesses.

GEORGE C. PRINGLE.
